United States Patent

Des. 241,158

Patented Aug. 24, 1976

241,158

CONVECTION STEAMER

David S. Schwerzler, Cleveland Heights, and V. Paul Lovejoy, Mentor, Ohio, assignors to Alco Standard Corporation, Cleveland, Ohio

Filed Dec. 2, 1974, Ser. No. 528,673

Term of patent 14 years

Int. Cl. D23—03

U.S. Cl. D55—1 E

FIG. 1

FIG. 2

FIG. 3

FIG. 4

FIG. 5

FIG. 1 is a front perspective view of a convection steamer, showing our new design;

FIG. 2 is a side elevational view thereof, the opposite side being a mirror image thereof;

FIG. 3 is a front elevation view thereof;

FIG. 4 is a rear elevation view thereof; and

FIG. 5 is a top plan view thereof.

We claim:

The ornamental design for a convection steamer, as shown and described.
